UNITED STATES PATENT OFFICE.

STEPHEN O. DE ORLOW, OF CHICAGO, ILLINOIS, ASSIGNOR TO WOODS MOTOR VEHICLE COMPANY, OF CHICAGO, ILLINOIS, A CORPORATION OF ILLINOIS.

HEATING SYSTEM FOR AUTOMOBILES.

1,278,880.

Specification of Letters Patent. Patented Sept. 17, 1918.

Application filed April 2, 1917. Serial No. 159,254.

To all whom it may concern:

Be it known that I, STEPHEN O. DE ORLOW, a citizen of the United States, residing at Chicago, in the county of Cook and State 5 of Illinois, have invented a certain new and useful Improvement in Heating Systems for Automobiles, of which the following is a full, clear, concise, and exact description, reference being had to the accompanying 10 drawings, forming a part of this specification.

My invention relates to heating systems for automobiles and more particularly to heating systems employed in connection with 15 water cooled internal combustion engines for the prevention of freezing of the cooling fluid used for cooling the engine cylinders.

It is one of the objects of the present invention to provide a heating system which 20 not only heats and circulates the cooling fluid or water contained within the water jackets provided on the internal combustion engine, while the automobile is standing idle on a street for several hours, or when stored 25 over night in a cold garage, but which also serves to heat the incoming gases of the engine so that complete volatilization of the gases occurs even though the engine has been standing idle and permitted to cool to 30 some extent.

A further object of the present invention is the provision of an element or insert arranged to be inserted between a carbureter and the intake manifold of an internal combustion engine, the element being provided 35 with a water jacket, arranged to receive heated water circulating through the internal combustion engine, and containing a heat generating device, preferably electrical, 40 which serves to heat the incoming gases and which serves to heat the fluid contained within the insert.

These and other objects of my invention will be more clearly brought out in connection with the accompanying drawings 45 wherein:

Figure 1 is a fragmentary side elevational view of an automobile showing the system of my invention applied thereto;

Fig. 2 is a top view of the insert or heating device which is inserted between the carbureter and the intake manifold;

Fig. 3 is a longitudinal cross sectional view taken along the line 3-3 of Fig. 2 and

looking in the direction indicated by the 55 arrows;

Fig. 4 is a longitudinal cross sectional view taken along the line 4-4 of Fig. 2 and looking in the direction indicated by the 60 arrows; and

Fig. 5 is a diagrammatic circuit drawing showing the electric circuit employed in connection with the heating device illustrated in Figs. 2, 3, and 4.

Similar characters of reference refer to 65 similar parts throughout the several views.

Referring first to Fig. 1, 6 illustrates the automobile chassis upon which is mounted the internal combustion engine 7. The internal combustion engine is provided with 70 the usual intake manifold 8, the outer end of which carries a flange 9 usually arranged to be attached to a carbureter. The flange 9 instead of being attached to a carbureter in the usual way is attached to the heating element illustrated at 10, the latter being provided with apertures 11 and 12 for the reception of bolts 13 and 14 which serve to connect the element 10 with the intake manifold. The lower end of the member 10 carries the bolts 15 and 16 arranged to attach 75 the carbureter 17 to the heating element.

The member 10 is provided with a longitudinal bore, as shown at 18¹, which affords communication between the carbureter and 80 the intake manifold so that in passing from the carbureter to the engine the gases must pass through the heating element 10. As most clearly shown in Figs. 3 and 4 the heating element is constructed so as to provide a water jacket 18 the upper end of 85 which connects with a coupling 19 and conduit 20 and the lower end with the coupling 21 and conduit 22. Extending around the inside of the element 10 is an electric heating coil 23 connected, as shown in Fig. 4, with the conductors 24, 25, and 26, the conductor 24 being attached to the upper end 90 of the coil, the conductor 25 to the lower, and the conductor 26 to the coil at a point 95 intermediate its ends.

The internal combustion engine 7 is provided with the usual water jackets in which a cooling liquid, such as water, is arranged to circulate. The upper end of the water 105 jacket or jackets provided on the engine 7 is connected by means of the conduit 27 with the upper end of the radiator 28. The lower

end of the radiator connects with the conduit 29 running to the center of a centrifugal pump 30 arranged to pump the water from the radiator through a conduit 31 into the 5 lower end or ends of the internal combustion engine water jackets. The conduit 20 extending from the upper end of the water jacket provided in the heating element connects with the engine water jacket as shown 10 at 20¹ in Fig. 1. The conduit 22 extends from the heating element to the engine water jacket as shown at 22¹ below the point of connection 20¹ of the conduit 20.

If we assume the engine 7 to be operating 15 and that no current is traversing the coil 23 of the heating element, water will be circulated from the radiator through the water jacket of the engine and back to the radiator in the usual way. At the same time a second 20 or auxiliary water circuit will be provided through the conduit 22, heating element 10 and conduit 20. As a result of circulating the heated water through the element 10 the incoming gases are heated and thoroughly 25 volatilized. If when the engine and pump are operating a current is sent through the heating coil 23 the element 10 will be heated to a greater extent and thus insure the volatilization of the gases.

30 When the engine is standing idle in a cold street or garage a current is sent through the heating coil 23 so as to heat the water contained within the water jacket of the element 10. This produces a flow of water 35 from the bottom of the radiator through the conduit 31 into the engine water jacket, through the conduit 22, heating element 10, the conduit 20, the engine water jacket and through the conduit 27 to the upper end of 40 the radiator. Freezing of water in the radiator and in the water jacket is thereby prevented.

In Fig. 5 I have illustrated at 23 a diagrammatic representation of the heating coil. One end of the coil 23 is connected by 45 means of the conductor 32 with one side of a battery 33, the other side of the battery being connected by means of a conductor 34 with a switch blade 35. The switch blade 50 35 is arranged to engage either one of the two contact points 36 and 37, the contact point 36 being electrically connected with one end of the coil 23 and the contact point 37 being connected by means of the conductor 55 26 with the coil at a point intermediate its ends. When the coil 23 is to be used for starting the engine the switch 35 is moved into contact with the point 37 so that an electric circuit is provided 60 through only a portion of the heating coil 23 thus generating a relatively great amount of heat. When the automobile is left standing in the cold the switch 35 is moved into contact with the point 36 so that the current 65 traverses the entire coil and thus creates a

less amount of heat, but an amount which is sufficient to prevent the water from freezing. If the automobile is standing in a garage and it is desired to use the garage lighting circuit instead of the battery an auxiliary 70 circuit is employed, as shown at 38. This circuit contains a socket or plug 39, arranged to be attached to the garage lighting circuit, and a pair of coils, one an induction coil 40, and the other a resistance coil 41, either of which can be connected in the circuit by means of the switch 42. Either one of the coils 40 and 41 is employed, depending upon the current traversing the auxiliary circuit 38.

Having thus described my invention what I claim as new and desire to secure by Letters Patent of the United States is:

1. The combination of an internal combustion engine having a water jacket, a radiator, a water jacket for the intake manifold of the engine, piping affording communication between the radiator and water jackets, and a heat generating element at the intake manifold for directly heating the incoming gases and for heating a fluid circulating through the jackets and radiator.

2. The combination of an internal combustion engine having a water jacket, a radiator, a water jacket for the intake manifold of the engine, piping affording communication between the radiator and water jackets, and an electric heat generating element at the intake manifold for directly heating the incoming gases and for heating a fluid circulating through the jackets and radiator.

3. A heater consisting of a tubular member arranged to be inserted between a carburetor and the intake manifold of an internal combustion engine and having a water jacket to receive a fluid for heating the gases passing through the member from the carburetor to the engine cylinder, and a heat generating element for heating the member 105 and thus the fluid contained within the water jacket thereof.

4. A heater consisting of a tubular member arranged to be inserted between a carburetor and the intake manifold of an internal combustion engine and having a water jacket to receive a fluid for heating the gases passing through the member from the carburetor to the engine cylinder, and an electric coil carried by the member for heating the same and thus the fluid contained within the water jacket thereof.

5. In an automobile the provision of a water cooled internal combustion engine, a radiator, means for circulating water heated 125 by the engine in proximity to the path of incoming gases of the engine whereby the gases are heated before reaching the engine cylinder, and a heat generating element located so as to heat both the incoming gases 130

and the water circulated in proximity to the path of the incoming gases.

6. In an automobile the provision of a water cooled internal combustion engine, a 5 radiator, means for circulating water heated by the engine in proximity to the path of incoming gases of the engine whereby the gases are heated before reaching the engine cylinder, and an electrical heat generating 10 element located so as to heat both the incoming gases and the water circulated in proximity to the path of the incoming gases.

7. In an automobile power plant the provision of an internal combustion engine having a water jacket arranged to receive a cooling fluid, a radiator having its upper end communicating with the upper end of the jacket and its lower end communicating 15 with the lower end of the water jacket, a pump interposed between the lower end of the radiator and the lower end of the water jacket for pumping the cooled fluid from the radiator to the engine water jacket, a 20 water jacket around the intake manifold of the engine, piping extending from the top of said intake manifold water jacket to the engine water jacket, piping extending 25 from the lower end of said intake manifold water jacket to the engine water jacket and 30 to a point below the connection of the first mentioned piping and engine water jacket, and an electrical heat generating element at the intake manifold of the engine for heat-

ing the incoming gases and for heating the 35 fluid in the intake manifold water jacket.

8. A heater for the intake of an internal combustion engine comprising a water jacketed part and an associated electric heating element disposed in heat transmitting relation with the wall of said water jacketed part for heating both the intake pipe and the contents of the water jacket, said jacket being arranged for connection with the water 40 circulating system of the engine. 45

9. An article of manufacture comprising a member having a bore therethrough, a water jacket therefor having ingress and egress openings and an electrical heating element disposed directly to heat the walls 50 of said bore and the contents of said water jacket.

10. The combination with an internal combustion engine having a water jacket and an intake manifold, of a heater having one side disposed in heat transmitting relation with gases passing through said manifold, and means disposed on the other side of said heater for absorbing the heat radiated from that side of the heater and conducting it to said water jacket. 55 60

In witness whereof I hereunto subscribe my name this 19th day of March, A. D. 1917.

STEPHEN O. DE ORLOW.
